ARTHUR H. RADASCH, OF SOUTH ORANGE, NEW JERSEY, ASSIGNOR TO THE BARRETT COMPANY, OF NEW YORK, N. Y., A CORPORATION OF NEW JERSEY

DISTILLATION OF TAR

Application filed May 31, 1929. Serial No. 367,366.

This invention relates to improvements in the production and distillation of tar in the by-product recovery system of a coal distillation plant. The invention includes both 5 the process and apparatus for carrying it out. According to the present invention tars of different composition are separately recovered from coal distillation gases and separately distilled to produce oils and pitches. 10 The invention is described more particularly as applied to a coke oven plant.

In the operation of coal distillation plants such as coke oven plants, the production of coke is in many cases the primary operation, 15 while in gas plants, the production of gas is a primary operation. In both cases coke and gas are produced and tar is recovered as a by-product. The tar is recovered by cooling the gases to condense and separate the tar therefrom.

The tar produced at coal distillation plants is to a large extent used as a fuel, particularly where coke oven plants are located adjacent to steel mills, in which case the tar is extensively employed as a fuel in open hearth 25 and other furnaces. A substantial proportion, however, of the tar recovered as a by-product at coke oven and gas plants is shipped to tar distillation plants and there subjected 30 to distillation for the production of distillate oils and pitch residues therefrom.

According to the present invention, the tar is not collected as a total tar product at the coal distillation plants but the tar is 35 collected in separate fractions, one of which is a heavy tar and another of which is a light tar or tarry oil and these respective heavy and light tars are separately distilled to pitch and the vapors resulting from the 40 separate distillations are together cooled to produce one or more distillate fractions. Pitches of the same or different melting points may be prepared from the different tars. The distillation of the separate tar- 45 fractions is advantageously carried out directly at the coal distillation plant by subjecting the separate tar fractions to direct contact with the hot coal distillation gases, thereby utilizing the heat of the gases for 50 distilling the tar fractions.

In the ordinary by-product coke oven plant the gases are collected from a number of coke ovens in a collector main and are there cooled by ammonia liquor or by ammonia liquor and tar and a considerable 55 part of the tar constituents separated from the gases in the form of a heavy tar. The gases are then passed thru a cross-over main to condensers where they are further cooled and where additional tar is separated there- 60 from usually in the form of a light tar or tarry oil. The heavy tar separated in the collector main and the light tar separated in the condensers are commonly combined and sold or employed as tar. Instead of combining the heavy tar and the light tar, I 65 keep these tar fractions separate and I take advantage of their difference in character by subjecting them separately to distillation thereby efficiently distilling the tar and recovering distillate oil and pitch products. The vapors resulting from the separate distillations may be cooled in the same condensing system to produce a single oil product or by fractional cooling more than one oil 70 fraction may be obtained.

The heavy tar separated from the gases in the collector main, which in coke oven operations may amount to 55 or 60% or more of the total tar, is relatively low in oil content and relatively high in pitch constituents, while the light tar or tarry oil separated in the condensers of a by-product coke oven battery contains a large proportion of oils and a relatively low percentage of pitch 80 constituents. This light tar or tarry oil comprises a relatively high percentage of tar acids and naphthalene, which products are present in much lower percentage in the 85 heavy tar from the collector main.

By separately distilling the heavier and lighter tars, I take advantage of the fact that the oil content of the lighter tars which contain only a smaller amount of higher boiling constituents, is more readily volatilized 90 from such oils than oils of similar boiling range can be volatilized from tars containing a larger percentage of higher boiling oils, as for example the tar from the collector main, or the tar formed by blending the 100

heavy tar from the collector main with the lighter tar or tarry oil from the condensers.

In distilling a tar fraction of lower boiling range, the temperature of the gases and vapors leaving the still is lower than the temperature at which the same vapors could be distilled from a mixture of this tar fraction of lower boiling range and a tar comprising oils of higher boiling range. Therefore by separately distilling the tar fractions, the lighter tars are distilled at a lower temperature and the maximum amount of tar may be distilled with any given quantity of heat.

According to this invention the vapors resulting from the separate distillations are cooled together in a single condensing apparatus and the distillate oils are obtained as one or more fractions. Because of the lower temperature required for distillation of the lower boiling oils present in the lower boiling tar fraction, when the fractions are separately distilled any decomposition of the vapors which would result from heating to higher temperatures is avoided. This results in an increased oil yield and the production of an oil free from the resulting decomposition products. The amount and composition of the pitch produced by the distillation is affected correspondingly.

According to the usual continuous methods of distilling tar, it is necessary to maintain the vapors resulting from the distillation at a relatively high temperature, i. e., the temperature at which the higher boiling oils are distilled from the tar. According to the present invention in distilling the lighter fraction or lighter fractions of tar, the temperature at which the gases are maintained is less than that necessary in those other methods in which a larger amount of heavier tar is blended with the lighter tar. By separately distilling the lighter tar and the heavier tar less decomposition of the vapors results since it is not necessary to maintain all of the vapors at the higher temperature necessary with such other methods.

Altho the separate distillations of the heavier and lighter tar fractions may be carried out in various ways according to this invention, it is advantageous to subject the different tar fractions to distillation by bringing them into intimate contact with hot coal distillation gases while these gases are at a sufficiently high temperature to effect the desired distillation. By bringing the tar fractions into intimate contact with the hot gases, for example, by repeatedly spraying the tar into the gases while they are at a high temperature approximating that at which they come from the ovens or retorts, the gases themselves will be scrubbed and freed to a greater or less extent from their heavier entrained carbon and pitch particles, while the tar fractions themselves will be rapidly distilled with

resulting enrichment of the gases in oil vapors. There will be obtained a pitch residue comprising undistilled constituents of the tar and such additional pitch constituents as are scrubbed from the gases. On subsequently cooling the gases, distillate oils will be obtained which are low in tar content and which may be substantially free from tar contaminations, i. e., the oils may be clean oils and directly merchantable as creosote oils or for other purposes.

The heavier and lighter tars may be distilled to pitches of approximately the same melting point, or pitches of different melting points may be made from the different tars. By combining the gases and vapors resulting from the separate distillations of the tar fractions and cooling the gases so as to fractionally condense the oils therefrom, I am able to obtain distillate oil fractions directly from the gases while employing only one condensing system. Instead of separately distilling the tar fractions and combining the resulting gases and vapors, I may distill the different tar fractions in the same gases, as, for example, by first distilling a heavier tar fraction in the gases and then employing the partially cooled gases to distill a tar fraction of lower boiling range. The use of one condensing system obviates the expense of two or more condensing systems which are necessary when the gases and vapors from the separate distillations are separately cooled.

The application of the present invention to the usual coal distillation plant does not require any substantial change or modification in the by-product recovery system or in the operation of such a system so far as the handling of the gases is concerned, except for the provision of separate collecting means for collecting and keeping separate the heavy and light tar fractions. Separate storage tanks or collecting tanks may be provided for the heavy tar from the collector main and the light tar from the condensers and where two or more fractions are obtained in the condensers, separate storage tanks may be provided for the different fractions.

Where the gases from the coal distillation plant are employed for distilling the separate tar fractions, provision must be made for using the gases while at a sufficiently high temperature. It is advantageous to spray the tar into the gases and to effect such intimate contact between the tar and gases as to scrub and detar the gases simultaneously with the distillation of the tar. In coke oven plants the gases leave the coke oven at a high temperature around 600-700° C. or higher. By drawing off the gases from the ovens directly into a distillation chamber without permitting any considerable cooling of the gases and by bringing the tar into intimate contact with the gases while they are still at a high temperature, the tar can be rapidly distilled and

a pitch residue produced therefrom at the same time that the gases are themselves scrubbed and freed more or less completely from suspended pitch particles and greatly enriched in oil vapors by the distillation.

5 Separate stills are provided for the separate tar fractions and in connection with these stills a single condensing system is provided for the distillate oils resulting from the distillations.

10 By regulating the rate at which the tar is sprayed into the gases, etc., the heavy tar can be distilled in gases which are maintained at a higher temperature and the light tar or tarry oil or the various fractions of such light tars will be separately distilled and generally a lower temperature will be maintained within these stills.

15 Where hot coal distillation gases are employed for the distillation of tar and where the gases enter the still at a temperature approximating that at which they leave the ovens, it has been found that where a high melting point pitch is produced it is advantageous to pass the tar and the gases thru the still in a generally concurrent direction.

20 If the tar and gases pass thru the still in a counter-current direction, the hot fresh gases which have a low vapor content come into contact with the nearly completely distilled

25 pitch and difficulties may arise from over-distillation of the pitch and the formation of coke as a result of the action of the fresh hot gases on the nearly completely distilled pitch.

30 Where, on the other hand, the gases and vapors resulting from the distillation and also the pitch are withdrawn from the same end of the still, the nearly completely formed pitch comes into contact with the nearly saturated gases cooled by previous distillation of

35 tar. The tendency to form coke or carbonaceous deposits is therefore greatly lessened. Furthermore, the fresh hot gases come into contact with the fresh tar and the tendency to form coke at this end of the still is also

40 small.

45 Where hot coal distillation gases are employed for distilling a total tar such as that produced by blending the various tars condensed from coke oven gases and where a high melting point pitch is produced, the pitch and enriched gases are advantageously withdrawn from the same end of the still and the nearly completely distilled tar comes in contact with gases containing a considerable percentage of higher boiling constituents.

50 When the heat of the gases is efficiently used, the gases leaving the still are almost saturated with such higher boiling oils. For this reason it is necessary to carry out the distillation at

55 a high temperature in order to distill from the pitch the last traces of higher boiling oils the removal of which is necessary to produce that particular pitch. On the other hand, if instead of distilling the total tar, various

60 tar fractions are distilled, the gases and

vapors leaving the still in which a tar fraction of lower boiling range is being distilled may leave at a lower temperature due to the fact that these gases do not contain as high a percentage of higher boiling oils as they leave the still. The distillation of the last traces of higher boiling oils, in order to produce a corresponding pitch, takes place at a lower temperature.

65 The extent to which the distillation of the respective tars is carried can be regulated and controlled depending upon the character of distillate oils desired and the pitch residues to be produced. Where the maximum oil yield is desired, both the heavy and light tars

70 can be distilled to pitches of high melting point, for example, around 400° F., or higher.

75 Where pitches of lower melting point are desired, the heavy tar may be subjected to a minimum of distillation to produce such low melting point pitch. The temperature necessary to distill the lower boiling oils from heavier tar is higher than that required to distill the same oils from a lighter tar but the time during which this heavier tar is

80 heated to effect the distillation is short. The time required to distill lighter tars to pitch

85 may be longer than the time required to distill heavier tar, but the temperature necessary

90 is not so great.

95 Where the tar is to be distilled in hot coke oven gases, and the temperature of the gases is uniform, a large quantity of the light tar may be sprayed into the hot gases in the form of a fine spray, so that the temperature of the gases will be reduced almost instantaneously to the temperature range desired. The quantity of light tar distilled per unit of time, by this process, will be large.

100 Light tar may advantageously be distilled to a high melting point pitch, while heavy tar is being distilled to a lower melting point pitch. High melting point pitch may be made from light tar with comparative ease and with a relatively high percent recovery

105 of distillate oil. This is due to the fact that the oils to be distilled are of relatively lower boiling range than are those present in the heavier tars. These oils recovered from the

110 lighter tars are relatively more valuable commercially than are the oils from the heavier tars. Therefore the distillation to harder pitches yields valuable oils at high percent recovery.

115 The distillation of the heavier tar to softer pitches is accomplished at relatively low temperature and with relatively little loss of oils due to the destructive effect of the high temperatures required if the heavier tars

120 be distilled to hard pitches.

125 The same gases may be employed to distill different tars to pitches of different melting points. First one tar, and then the other may be sprayed into the same hot gases and be distilled therein. The resulting gases will be enriched by vapors from each distillation,

and on cooling a composite oil will be produced. The gases may first be employed for distilling a heavier tar fraction to a relatively high melting point pitch, and the resulting gases be then employed for distilling a lighter tar or tarry oil to a pitch of lower melting point, although in such a case some destruction of heavy oils in the heavy tars will be experienced. The vapors from both distillations will be treated in the same condensing system.

Where the collection of separate pitches is not important, but efficient distillation is desired, the lighter tar or tarry oil may be only partially distilled in the one still to remove all or the greater proportion of the lower boiling oils and produce a low melting point pitch. Further distillation of this partially distilled product may be carried on in the still employed for distilling the heavy tar, simultaneously with the distillation of the heavy tar. Such partial distillation of the light tar or tarry oil and further distillation of the resulting residue in a separate still in which heavy tar is simultaneously distilled is particularly advantageous where a high melting point pitch is desired. In such a process, the temperature of the still employed for distilling the tarry oil need not be high enough to produce a high melting point pitch therein, but merely high enough to distill off the lower boiling oils, and such distillation can be carried on most efficiently therein.

Whether one pitch product is obtained in this manner, or the heavy and light tars are separately distilled to pitches of the same melting point, or pitches of different melting point, separate distillation of the tar fractions is more efficient than the preparation of corresponding pitches by distillation of a total tar comprising the several tar fractions. The oil yields are higher and the heat consumption is less.

The invention will be further described in connection with a by-product coke oven plant. It will be understood by those skilled in the art that the invention is applicable to other types of coke ovens and other coal carbonization plants in which various grades of tar may be fractionally separated from the gases as in a gas collector main and a condensing system.

In the accompanying drawings,

Fig. 1 is a general plan view of a somewhat conventional character showing a by-product coke oven plant provided with separate collecting and handling equipment for collecting and keeping separate the heavy and light tars and for separately subjecting these to distillation and combining the gases and vapors resulting from the distillation and simultaneously cooling them in a single condensing system;

Fig. 2 is an elevation of the still shown in Fig. 1;

Fig. 3 is an end view of the still; and Figs. 4 and 5 show a modified form of apparatus.

Referring to the drawings, 5 indicates a coke oven battery equipped with the usual uptake pipes 6 and collector main 7 provided with center-box 8, from which a cross-over main 9 connects in the usual way with condensers 10. The goose-necks of the uptake pipes and the collector main 7 may be sprayed with ammonia liquor, or tar and ammonia liquor, through sprays 11 and 12. The heavy tar and the ammonia liquor, which drain from the collector main into the center box 8 are drawn off thru pipe 14 to the decanter 15. Tar and ammonia liquor from the cross-over main may also be drawn off into this same decanter thru pipe 16, or may be separately collected, or may be collected with the light tar from the condensers 10. The ammonia liquor and tar will be drawn off from the decanter 15 to separate storage tanks 17 and 18.

Light tar or tarry oil and ammonia liquor are drawn off from the condensers 10 to the decanter 20 from which the ammonia liquor and light tar are separately collected in the storage tanks 21 and 22. An exhauster 23 is provided for drawing the gases thru the system. Means for recovering ammonia and light oils (not shown) may be provided beyond the exhauster.

Stills 24 and 25 are provided at the rear of the ovens. Each of these stills is adapted to receive hot gases from several of the ovens of the battery 5. By properly manipulating the valves 26 in the goose-necks of the uptake pipes 6, connected with the usual collector main and valves 27' and 28' in the goose-necks 27 and the uptakes 28, which connect selected ovens with the stills at the rear of the ovens, the gases from those ovens which are connected with both the usual collector main and one of the stills may be directed to either the usual collector main 7 or one of the stills 24 and 25. By means of these valves the amount of hot gases passing thru the stills may be regulated to effect the desired distillation.

Each of the stills is provided with agitating means for bringing the tar into intimate contact with the hot gases. For this purpose a smooth roll or cylinder 29 is shown, dipping to a slight extent into the tar in each still. The gases are sprayed with tar atomized by rapid rotation of this roll. The degree and intensity of spray can be regulated by regulating the extent to which the roll dips into the tar, and the rate at which the roll is rotated. The motor 30 is connected with the roll, and by regulating its speed the rate of rotation of the cylinder is controlled. By rotating the roll at a speed of 900-1200 R. P. M. such an intense spray of tar may be thrown up into the gases passing thru the

main as to result in substantial detarring of the gases. On cooling the resulting gases, clean oils are obtained. Instead of a smooth cylinder, a corrugated or other cylinder, or sprays, or other means, may be employed for bringing the tar into intimate contact with the hot gases.

In operating the apparatus tarry oil or light tar from the tank 22 is pumped by pump 31 into the settling chamber 35, the amount being regulated by the valve 32 and by the pump. The tar is sprayed into the settling chamber thru line 35' and falls upon the baffles 36'. The gas in passing up thru the baffles preheats and partially distills the tar. The tar is collected at the bottom of the settling chamber and is run to still 25 thru line 25'. By proper regulation of the valves 27' and 28' in those uptake pipes connected to the still 25 and the valves 26 in the corresponding uptake pipes connected with the usual collector main 7, gas from the desired number of ovens can be passed thru the still. By controlling both the supply of light tar and the supply of hot gases and the intimacy of contact, the extent to which the distillation is carried can be governed.

Pitch resulting from the distillation is drawn off thru a coke trap and leveling arm 33' into the tank 33. A portion of this pitch may be returned to the still thru the line 34 for retreatment where this is desirable. The position of the leveling arm 33' determines the level of the tar or pitch in the still. A settling chamber 35 which allows liquid particles entrained in the gases to settle out and to return to the still is shown but such settling means is not always required but is desirable if it is desired to have the oils recovered from the gases by cooling, as free as possible of contamination by tar or tarry matters.

Heavy tar from the receiver 18 is supplied thru the lines 39 and 35' to the settling chamber 35. It passes then thru line 24' to still 24 where it is distilled to produce pitch. The extent to which the distillation is carried may be regulated in the manner described in connection with the distillation of the light tars, except that when pitches of high melting point, e. g. 300-400° F. are produced, the pitch is conveniently handled by granulating it in the trough 42' in a stream of water. The pitch and water then flow to tank 41 from which the pitch may be recovered. When soft or medium pitches are made they may be collected as liquid pitch in tank 41'.

In case hard pitch or pitch of melting point of 300-400° F. is made in still 25, a granulating trough similar to 42' and a granulated pitch tank similar to 41 will be required. In many cases the same tank 41 can be used.

The gases and vapors of oils of lower boiling range from the still 25 are combined with the gases and vapors of oils of higher boiling

range from the still 24 and together they pass to the condensers 37 which are here shown as fractional condensers of the direct type, although other condensing means may be employed. The gases from the still 24 which are the gases carrying heavier vapors resulting from the distillation of heavy tar may advantageously pass thru a condenser 38 before being admitted to the condensers 37 in order that higher boiling constituents may be recovered from these gases before combining them with the gases and vapors from the still 24, although condenser 38 need not be employed if the collection of a separate heavy oil fraction from the heavy tar is not desired.

In the arrangement described the heavy tar from the collector main will be distilled in the still 24 and the light tar from the condensers will be distilled in the still 25. Pitches which may be of different melting points are produced as residues of the distillations and they are separately drawn off into the tanks 33 and 41 or 41'. Due to the different composition of each of the tars distilled, each still is operated differently. The rate at which the tar is fed to each still, the rate at which pitch is withdrawn, etc., are varied to produce the desired distillation in the still.

Where only one pitch product is desired, and particularly where a high melting point pitch is desired, the light tar may advantageously be subjected to a partial distillation in the still 25 to remove only the light oils therefrom. This partly distilled residue is then passed thru the line 43 to the still 24 and further distilled therein simultaneously with the heavy tar from the collector main. In this method of operation, the condenser 38 may advantageously be employed to condense the higher boiling oils resulting from the distillation of the residue carried over by the line 43 to the still 24 and the higher boiling oils contained in the heavier tar. The lower boiling oils are collected in the condensers 37 which are common to both stills. According to this method, the total pitch residue from the distillation of both tars will be produced in the still 24 and will be drawn off as a total pitch product into the tank 41 or into tank 41'. Where only a part of the pitch from the still 25 is further distilled in the still 24, different pitch products will be obtained in the tanks 33 and 41 or 41'.

Figs. 4 and 5 show a modified form of apparatus in which the same hot coal distillation gases are employed for distilling tars of different boiling range. The hot gases from selected ovens of the coke oven battery 50 pass through the uptake pipes 51 into a hot gas header 52 and thence into the still 53. From this still the hot gases pass to the still 54 and from there to the condensers 55 and 56. An exhauster 57 is shown for drawing the

gases thru the system. The uptake pipes 51 and the hot gas header are advantageously insulated as shown at 58 and the stills 53 and 54 may also be insulated to advantage. Each of the stills is equipped with a spray roll as shown at 59 and 60 driven by a motor in the manner described in connection with the stills 24 and 25 of the preceding figures.

The gases from the ovens of the battery not 10 sent thru the hot gas header 52 are collected in the collector main 61. They are cooled in the ordinary manner as with ammonia liquor supplied from the line 62. The ammonia liquor and heavy tar which separate in the collector main are drawn off into the decanter 63. The tar is separately collected in the storage tank 64. From the collector main 61 the gases pass to the condensers 65. Tarry oil and ammonia from the condensers are collected in the decanter 66. From this decanter the tarry oil is separately collected in the storage tank 67. This tarry oil is lighter than the heavy tar collected in the tank 64 and comprises oils of lower boiling range than 25 the oils contained in the heavy tar.

The heavy tar from the tank 64 is distilled in the still 53. This tar is supplied thru the line 70 by the pump 71 and sprayed into the tower 72 thru which the hot gases and vapors 20 from the still 53 pass on the way to the still 54. The tar is advantageously collected in the bottom of the tower and fed thru the line 72' to the still 53 at the end at which the hot gases enter from the hot gas header 52. The 25 tar is sprayed up into the gases by the roll and the gases are scrubbed and substantially detarred and the heavy tar is distilled. The pitch produced is withdrawn thru the adjustable levelling arm 74 and collected in the trough 75. The gases enter the still 53 at a high temperature and the heavy tar may be distilled to pitch of a high melting point within the still 53.

Where a high melting point pitch is produced it may be granulated by sudden cooling in a stream of water, supplied thru the pipe 75'. The granulated pitch and water are drawn off thru the trough into suitable means for the separation of the pitch and the 50 water.

The gases leaving the still 53 and the tower 52 are only partially cooled and only partially saturated with oil vapors. They pass to the still 54 where they are employed for distilling oils of lower boiling range from the tarry oil. The tarry oil is supplied from the storage tank 67 to the still 54 thru the line 76 by means of the pump 77. The tarry oil is preferably sprayed into the gases in the 55 tower 73 thru which the gases and vapors pass as they leave the still 54. The tar is partially distilled in the tower and the residue 60 may be drained directly into the still or it may be drawn off from the bottom of the 65 tower by means similar to those shown in

tower 72 and admitted to the still at the end at which the gases and vapors from the tower 72 enter the still. The gases and vapors enter the still 54 thru the main 78.

According to the arrangement shown in 70 the drawings, the tarry oil is sprayed into the gases and vapors in the tower, and drains into the still thru the main 79 connecting the tower with the still 54. Within the still the tarry oil is brought into intimate contact with 75 the hot gases and vapors by means of the rapidly rotating roll 60. The gases and vapors entering the still 54 thru the main 78 have been somewhat cooled. They are only 80 partially saturated with oils as a result of the distillation in the still 53 and are employed for distillation of the tarry oil in the still 54. The extent to which the tarry oil can be distilled depends upon the extent to which the 85 gases are cooled and saturated by the distillation which takes place in the still 53, the rate at which the tarry oil is supplied to the still 54, its temperature, etc. The pitch produced in the still 54 may be a low melting point pitch or a pitch of higher melting point. It 90 is withdrawn from the still thru the leveling arm 80. Where a pitch of low melting point is produced, it may advantageously be collected in a cup such as the cup 81 and drained into the tank 82.

The hot distillation gases are first employed for distilling tar from the collector main. They are then brought into intimate contact with the tarry oil and the tarry oil is distilled. The gases carrying vapors resulting from the 100 distillation of the heavy tar and tarry oil pass thru the tower 73 thru the main 83 into suitable condensers. Indirect condensers 55 and 56 are here shown for fractional cooling of the gases and vapors and the recovery 105 of separate clean oil fractions. The cooling may be so regulated that creosote oil is condensed in the condenser 55 and collected in the storage tank 84 and an oil boiling in the 110 range of carbolic oils separates in the condenser 56 and is collected in the storage tank 85. Means for the recovery of ammonia, etc. may be located beyond the exhauster 57.

Where further distillation of the pitch resulting from the distillation of the tarry oil 115 is desired, this pitch may be further distilled in the still 53. For this purpose the line 86 and pump 87 are shown connecting the tank 82 with the line 72' which conveys the undistilled residue of the heavy tar from the tower 120 72 to the still 53. With such equipment heavy tar from the storage tank 64 may be preheated and partially distilled in the tower 72 and then brought into the still 53 thru the pipe 72'. This heavy tar which has been partially distilled and preheated is mixed with the pitch from the still 54 supplied thru the line 86 from the tank 82. This pitch is advantageously pumped to the still 53 while it 125 is still hot. The gases and vapors resulting 130

from this distillation pass thru the tower 72 to the still 54 where they are employed for distillation of tarry oil from the tank 67.

It will thus be seen that the present invention takes advantage of the fractional separation of tar in the by-product recovery system of a coal distillation plant to produce two or more separate fractions, keeping these fractions separate and subjecting them separately to distillation for the production of distillate oils and one or more pitches, and cooling the vapors from the separate distillations in a single condensing system to produce one or more distillate oils.

16 While I have described the invention more particularly in connection with a coke-oven plant, it will be understood that it is applicable to other coal distillation plants, as gas retort plants, etc.

20 I claim:

1. The improved method of producing distillate oils and pitches from coal tar which comprises fractionally condensing the tar from hot coal distillation gases and thereby 25 producing a plurality of tar fractions, including a heavy tar and a light tar fraction, subjecting the light tar to distillation to separate lower boiling constituents therefrom and to produce a heavy tar or pitch, combining such 30 heavy tar or pitch with the heavy tar fraction and distilling the mixture, and combining the gases and the vapors resulting from the distillations and cooling them to separate distillate oils therefrom.

35 2. The improved method of producing distillate oils and pitch from coal tar which comprises fractionally condensing tar from hot coal distillation gases and thereby producing a plurality of tar fractions including a heavy 40 tar and a light tar fraction, separately distilling the heavy tar and light tar fractions, partially cooling the vapors resulting from the distillation of the heavy tar fraction to separate a heavy oil, combining the resulting vapors with the vapors from the distillation of the light tar fraction and cooling the combined vapors to produce distillate oils.

45 3. The improved method of producing distillate oils and pitch at a coke oven plant 50 which comprises fractionally recovering tar from hot coal distillation gases and thereby producing a plurality of tar fractions including a heavy tar and a light tar fraction, separately bringing the heavy tar and the 55 light tar fractions into direct and intimate contact, in series, with the same hot coal distillation gases, whereby separate pitch products are produced, and cooling the resulting gases and vapors in a condensing system to 60 separate distillate oils from the gases.

65 4. The improved method of producing distillate oils and pitches at coke oven plants, which comprises collecting the gases from a plurality of coke ovens in a gas collector main, 70 cooling the gases therein to separate a heavy

tar, subsequently further cooling the gases to separate a light tar or tarry oil, keeping the heavy tar and tarry oil separate, bringing the heavy tar into direct and intimate contact with hot coal distillation gases whereby the 75 tar is distilled and a pitch is produced, bringing the gases and vapors resulting from this distillation into direct contact with the tarry oil to distill the tarry oil and produce pitch, and cooling the resulting gases to separate 80 oils distilled from the heavy tar together with oils distilled from the light tar.

5. The improved method of producing distillate oils and pitch at a coke oven plant, which comprises fractionally recovering tar 85 from hot coal distillation gases and thereby producing a plurality of tar fractions including a heavy tar and a light tar fraction, separately bringing the heavy tar and the light tar fractions into direct and intimate contact, 90 in series, with the same hot coal distillation gases, uniting the pitch produced by distillation of one of the tar fractions with the other tar fraction and distilling it therewith to produce a pitch product, and cooling the 95 gases and vapors resulting from the distillations in a condensing system to separate distillate oils.

In testimony whereof I affix my signature.

ARTHUR H. RADASCH.
